UNITED STATES PATENT OFFICE.

JOHN V. ROWAN AND ADOLPH ZAMRSKY, OF FORT STEVENS, OREGON.

CIGAR-HOLDER.

1,145,799.

Specification of Letters Patent.

Patented July 6, 1915.

Application filed April 23, 1912. Serial No. 692,553.

To all whom it may concern:

Be it known that we, JOHN V. ROWAN and ADOLPH ZAMRSKY, citizen of the United States and subject of Austria, respectively, residing at Fort Stevens, in the county of Clatsop and State of Oregon, have invented new and useful Improvements in Cigar-Holders, of which the following is a specification.

- 10 This invention relates to cigar holders, the object in view being to provide a holder or receptacle for containing the major portion of the cigar and gathering and retaining therein the ashes and smoke, while the 15 extremity of the cigar is allowed to protrude through the adjacent end of the holder so as to be held in the mouth of the smoker in the usual way. The construction of the holder thus allows the smoker to enjoy the 20 full flavor of the cigar while preventing any possibility of the smoke escaping so as to injure or affect the eyes, the holder also acting as a repository for the residue in the shape of ashes.
- 25 With the above and other objects in view the invention consists in the novel construction, combination and arrangement of parts as hereinafter fully described illustrated and claimed.
- 30 In the accompanying drawings: Figure 1 is a longitudinal section through the improved cigar holder showing the cigar in elevation. Fig. 2 is a side elevation of the main section of the holder. Fig. 3 is a sectional view of the end piece or smaller section of the holder.

The cigar holder contemplated in this invention comprises a main section 1 which is for the greater part cylindrical and of 40 uniform diameter, the size thereof adapting it to receive and contain the larger portion of the cigar designated at 2. The outer end of the section 1 is preferably reduced or tapered to conform to the shape of the lighted end of the cigar and is closed at such end except that it is provided with a large number of fine perforations 3 to admit oxygen to provide for proper combustion of the cigar and to prevent the same from becoming extinguished. At its other end the section 1 is enlarged as shown at 4 and internally threaded as shown at 5 to receive the externally threaded flange 6 of the end piece or smaller section 7. In this way the two 55 sections of the holder are detachable so that

they may be fitted upon the cigar preparatory to smoking the same.

The end piece or smaller section 7 has a frusto-conical portion as shown at 8 and is provided upon the interior of the frusto-conical part with shallow compressing threads 9 in the form of spiral corrugations which are rounded adapting them to force their way into the body of the cigar as the end piece is forced upon the tapered end of 65 the cigar, without in any way mutilating or injuring the cigar and its wrapper. This has the effect of confining the end piece or smaller section 7 tightly around the cigar so as to prevent the escape of smoke adjacent 70 to the mouth.

It will be understood that the end piece or section 7 is first securely placed upon the tapered end portion of the cigar in the manner illustrated in Fig. 1 and thereafter the 75 main section 1 is placed over the remainder of the cigar and coupled to the smaller section by the means above described. The device thus answers the purpose of a cigar holder without the undesirable feature of 80 having a portion of the holder in the mouth. Furthermore the holder retains the ashes therein and largely prevents the escape of smoke from the burning end, thus protecting in a large measure the eyes especially while 85 smoking during writing or reading periods. Since oxygen enters in large quantities only after the smoker draws his cigar, it naturally follows that the cigar is conserved; however, sufficient air is admitted at all 90 times to prevent the cigar from going out.

The holder may of course be constructed of any suitable non-inflammable material and as it is sectional it may be readily and thoroughly cleaned. Furthermore the smoker 95 may carry a partially consumed cigar in the pocket without danger of soiling the clothes.

It will be noted that the major portion of the main section of the cigar holder is imperforate and therefore well adapted to retain the ashes, preventing the same from sifting out of the holder. The main section is formed at its open end with an internally threaded enlargement which is designed to receive the externally threaded cylindrical portion of the frusto-conical end piece or section as shown in Fig. 1. It will also be noted that in addition to the externally threaded cylindrical portion, the end piece or smaller section is spirally corrugated to 105 110

provide internal cigar compressing threads and corresponding external threads thus enabling the end piece to be firmly grasped and held between the fingers without touching the projecting end of the cigar itself.

5 We claim:—

- A cigar holder and ash receptacle of the class specified, comprising a hollow cylindrical main section adapted to receive and hold the major portion of a cigar and having one end thereof closed and perforated and the other end thereof open and provided with an internally threaded enlargement, the major portion of said main section 10 being imperforate, and a separable frusto-

conical end piece or section having a cylindrical and externally threaded portion to screw into the threaded enlargement of the main section and another portion spirally corrugated to form internal cigar compressing and gripping threads and corresponding external finger gripping threads. 20

In testimony whereof we affix our signatures in presence of two witnesses.

JOHN V. ROWAN.
ADOLPH ZAMRSKY.
